WASHING MACHINE

Filed Dec. 8, 1927

UNITED STATES PATENT OFFICE

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

WASHING MACHINE

Application filed December 8, 1927. Serial No. 238,552.

This invention has reference to washing machines and it has for its principal object to improve the agitator structure thereof, in the provision of a novel driving connection 5 between the agitator and agitator operating shaft; in the provision of a novel manner of supporting the agitator in its relation to the tub bottom; in the provision of a novel means to prevent clothing and other material from 10 entering under the edge of the agitator, likewise dirt and other foreign matter, and in the provision of a novel driving means for the agitator operating shaft.

A further object of the invention is to provide an agitator operating shaft having a 15 preferably floating upper end below the normal water level in the tub; such floating end of said shaft facilitating the easy and convenient connection of the agitator with said 20 shaft.

A still further object of the invention is to provide a vertically disposed tubular stem forming a housing for the agitator operating shaft and a bearing means for an upstanding 25 sleeve of the agitator; said stem having a bearing support at its base, which provides a support for and on which the agitator rotates.

Other and further objects will more fully 30 appear from the following description.

That the invention may be more fully understood, reference is had to the accompanying drawings forming part of this description, illustrating a preferred embodiment of 35 the invention, in which:

Fig. 1 is a plan view of a washing machine tub with my improved agitator mechanism therein;

Fig. 2 is a vertical cross-section through 40 tub and agitator mechanism;

Fig. 3 is a detail, partly in section, showing the stem and bearing support thereon for the agitator and the associated agitator operating shaft, and

Fig. 4 is a view somewhat similar to Fig. 2, except that the off-set driving shaft and the gearing to the agitator operating shaft are shown.

Like characters of reference denote corresponding parts throughout the figures.

The tub 1 is here shown of the conventional square type having preferably a substantially flat bottom 2 throughout its area above which is supported to be oscillated an agitator or washing element 3. The flat bottom 2 is shouldered at 4, forming an annular offset, with the portion 2 of the bottom slightly depressed, and from such shouldered portion the bottom slopes upwardly into the sides of the tub. I have shown the bottom 2 provided with an opening 5 through which passes a journal bearing 6 for a vertically disposed shaft. In Fig. 2 this opening is axially of the tub, while in Fig. 4 this opening is off-set from the axis of the tub. In Fig. 2 the journal bearing 6 is a stem extension from a vertically upstanding stem 7, while in Fig. 4 the journal bearing is an extension from a gear casing section 8 adapted to be coupled to the base of said stem 7. In each instance suitable packing is shown over and underlying the bottom 2 and surrounding the extension 6 to prevent leakage, a nut 9 having a threaded connection with said extension to firmly secure the parts in place.

The stem 7 extends to a point in the tub above the normal water level therein, is open at its upper end and formed or provided interiorly at or near this point with a bearing surface 10. At its lower end said stem is formed or provided with a stepped base 11 which provides a bearing support on which is supported and rotates the agitator 3. This stem 7 serves as a housing in which oscillates the upstanding agitator operating shaft 12, which, in Fig. 2 passes up through and has a journal bearing in the extension 6 of the stem and the base thereof, while in Fig. 4 it passes through and has a journal bearing relation in the base of the stem and terminates there-beneath without passing through and out of the bottom 2 of the tub, as in Fig. 2. The upper end of the shaft 12, in each instance, terminates short of the stem end having the bearing surface 10 and therefore below the normal water level in the tub and preferably has, what is termed a floating position in the upper portion of said stem 7, and is easily alignable with the vertically extended sleeve 13 of the agitator when seating the same for 100

operative position in the tub. The upper end of the shaft 12 being provided with a preferably squared end 12' to adapt a slip on and off driving connection between the sleeve 13 and said shaft, whereby oscillations of said shaft may be imparted to the agitator to impart a preferably alternate rotary movement thereto.

The agitator 3 and sleeve 13 constitute a unitary structure, whether cast in one piece, or in several pieces and welded or otherwise connected. Said agitator comprises a preferably disc-like member 3', which, when it is in operative position in the tub lies immediately above the bottom portion 2 and is formed or provided with a radially arranged annular flange 14, whereby to form, together with the base of the disc a structure complementary to the shoulder 4 in the tub bottom, whereby to prevent clothing and other materials from getting under the agitator and to prevent dirt and other foreign matter from also getting under said agitator. Disposed radially and upstanding from the surface of the disc and terminating in its base and said sleeve are a plurality of baffles, wings or agitating vanes 15, common in structure of like character. The sleeve 13 extends downwardly to a point below the top surfaces of the baffles 15 and is provided interiorly at or near its lower terminal with an externally disposed bearing surface 16 rotatable on the lower surface of the sleeve 7, while the upper end of said sleeve 13 normally extends above the end of the stem 7, at which point it is formed or provided with an inturned downwardly extending bearing member 17, overlying the upper end of the stem and terminating downwardly in the stem 7 below its upper end and below the normal water level in the tub. The member 17 rotates on the bearing surface 10 within the stem 7 and the lower end of said member 17 is formed or provided with a socket or opening 18 which preferably conforms to the shape of the end portion 12' of the shaft 12, whereby a slip on and off connection may be had between the sleeve 13 and the shaft 12 to transmit movement from said shaft to the agitator and its sleeve. The floating of the upper end of the shaft 12 facilitating the easy and convenient attachment of the part 17 of the sleeve 13 with the upper end of the shaft 12, as such floating end will allow the shaft to be easily aligned with the part 17 of the sleeve 13. As shown, the stem 7 forms a housing for the shaft 12 which has a journal bearing with said stem and its base only at the latter point, being allowed to float at its upper end and the inturned portion of the sleeve 13 has a bearing relation at its upper end interiorly of the stem 7 and externally of the stem at its lower end; the said sleeve, however, being supported on and by the stem 7 only at its lower end and then by the base 11, as will be understood.

The agitator operating shaft 12, as shown in Fig. 2, would have its operative connection with its driving means below the tub bottom, whereas, as shown in Fig. 4 this operative connection is above the tub bottom and beneath and confined within the agitator. As thus arranged the base of the stem 7 is coupled or secured to the gear housing section 8, which, in addition to having a connection with the bottom 2 of the tub through and by means of the extension 6, may be secured to said bottom in any other suitable manner and by any suitable means. Also in this arrangement, the agitator operating shaft 12 does not extend downwardly or upwardly through the bottom of the tub, but terminates in the casing 8 and has connected thereto a gear wheel 19 in mesh with and adapted to receive its power from a gear pinion 20 on the upper end of a driving shaft 21 having a journal bearing in the base of the stem 7 and being off-set with respect to the axis of the tub 1 passes down through (or up through, as the case may be) and has a journal bearing in the extension 6, its lower end having a driving connection with any suitable driving mechanism, not shown. This arrangement of drive to the agitator operating shaft will allow for a different ratio of speeds from the driving shaft to the agitator operating shaft, or a uniform speed therebetween, as may be desired. Also, the use of such gearing, to permit a different ratio of speeds between the driving and agitator shafts will eliminate many of the elements ordinarily included in the usual and customary transmission gearing. It is also obvious that by this arrangement the gearing is fully protected against water entering the housing, does not interfere with the agitator and provision is made to prevent leakage around the sleeve 6, both in the form shown in Fig. 4, as well as in Fig. 2.

Furthermore the sleeve of the agitator is above the normal water level in the tub, so that the coupling between said sleeve and the upper end of the shaft 12, even though positioned below such normal water level is protected against leakage or overflow into the stem 7.

What I claim is:

In a washing machine, in combination, a tub, a tubular stem having a journal bearing in the bottom of the tub and extending to a point above the normal water level in the tub and provided with an interiorly arranged bearing surface at its upper end and with an exteriorly arranged bearing surface at its lower end, a shaft extending up into the stem and having a bearing through its lower end and terminating in a driving floating end within the stem below the normal water level in the tub and an agitator including an upstanding sleeve having a bearing on the exteriorly arranged bearing surface on the low-

er end of the stem and provided with an inwardly depending bearing member at its upper end having a bearing relation with the exteriorly arranged bearing surface at the upper end of the stem, and the terminal of said bearing member adapted to have a slip on and off driving connection with the driving end of said shaft.

In witness whereof, I have hereunto affixed my hand this 2nd day of December, 1927.

ALPHEUS W. ALTORFER.
